(57) CLAIM

The ornamental design for a hexagonal game piece holder with bowl, as shown and described.

DESCRIPTION

FIG. 1 is an isometric view of a hexagonal game piece holder with bowl.

FIG. 2 is a top view of a hexagonal game piece holder with bowl.

FIG. 3 is a bottom view of a hexagonal game piece holder with bowl.

FIG. 4 is a right-side view of a hexagonal game piece holder with bowl. The left-side view, which is omitted from the figures, is a mirror image of the right-side view; and, FIG. 5 is a side view of the hexagonal game piece holder with bowl that is rotated 30 degrees with respect to the view in FIG. 4.

In the drawings, the broken lines depict portions of the hexagonal game piece holder with bowl that form no part of the claimed design.

The hexagonal game piece holder with bowl may be used on a tabletop or other surface to hold game pieces, dice, and similar objects.
